UNITED STATES PATENT OFFICE.

JOHN PHILLIPS MERN, OF BROOKLYN, NEW YORK, ASSIGNOR OF ONE-HALF TO JOHN E. DEIGNAN, OF BROOKLYN, NEW YORK; JAMES H. DEIGNAN ADMINISTRATOR OF SAID JOHN E. DEIGNAN, DECEASED.

VALVE MECHANISM.

No. 861,580.

Specification of Letters Patent.

Patented July 30, 1907.

Application filed January 2, 1906. Serial No. 294,254.

To all whom it may concern:

Be it known that JOHN PHILLIPS MERN, a citizen of the United States, residing at Brooklyn, in the county of Kings and State of New York, has invented 5 a new and useful Valve Mechanism, of which the following is a specification.

This invention while relating more particularly to valve seat structures of hydrants, is not necessarily limited thereto, but may be advantageously employed in other apparatus, wherein valves are used.

10 The principal object of the invention is to provide a novel and simple valve seat that can be readily placed in position and removed, so that if the valve mechanism becomes worn or deranged, access thereto 15 may be readily gained, and the injured or inoperative parts repaired or replaced with ease and expedition.

A further object is to provide securing means for 20 the valve seat, whereby the latter may be effectively fastened in the casing, said means also preventing leakage through the joint between the seat member 25 and casing.

The preferred embodiment of the invention is illustrated in the accompanying drawings and described in the following specification.

25 In said drawings:—Figure 1 is a vertical sectional view through a hydrant showing the valve mechanism in place therein, together with the positioning and locking tool employed in connection therewith. Fig. 2 is a sectional view through the said mechanism 30 on an enlarged scale. Fig. 3 is a horizontal sectional view, taken on the line 3—3 of Fig. 2. Fig. 4 is a horizontal sectional view on the line 4—4 of Fig. 1. Fig. 5 is a detail perspective view of the valve seat member. Fig. 6 is a side elevation of the head of the 35 tool employed in positioning and securing said member.

In the embodiment illustrated, a coupling elbow 40 or casing 7 is employed having a valve chamber 8 therein, and an upper inwardly extending wall portion 9 provided with a central opening 10, forming a valve seat receiving socket. A casing 11 is suitably mounted on the elbow or casing 7, and is provided at its upper end with the usual outlet nipples 12. The inwardly extending wall portion 9 of the casing 45 7 is provided with spaced lugs 13, and the marginal portions of said wall about the opening 10 is beveled, as shown at 14. This beveling includes the upper sides of the lugs 13, as shown in Fig. 3.

A detachable valve seat member in the form of a 50 sleeve 15 is employed, which sleeve is arranged to enter the opening 10 between the inner ends of the lugs 13. The lower portion of said sleeve is provided with a plurality of outwardly extending lugs 16 ar-

ranged to pass through the spaces between the lugs 13 of the casing and engage the underside of said 55 lugs 13 after having been so passed through, and upon the turning of the sleeve. Stops 17 arranged at the ends of the lugs 16, limit the said turning movement. An intermediate portion of the outer face of the sleeve or valve seat member is beveled, as shown at 18. This 60 portion is disposed in opposition to the beveled margin 14 of the casing wall 9 when the sleeve is in place therein. The upper end of the sleeve is exteriorly threaded, as shown at 19, and screwed thereupon is a clamping nut 20. A packing gasket 21 65 preferably formed of sheet lead or other suitable material is arranged beneath the clamping nut, and is adapted to be forced thereby into the tapered annular recess formed by the beveled portions 14 and 18. The lower end of the sleeve 15 is interiorly beveled, 70 as shown at 22, forming an annular seat to receive the usual valve 23, said valve being carried by the lower end of the stem 24 extending longitudinally through the casing 11 and operated in any desired manner.

The clamping nut 20 is provided with upwardly extending studs comprising stems 25 having heads 26 at their upper ends. These studs are arranged to be engaged by the lower disk head 27 of a positioning and securing tool 28, the said head 27 being carried by a tubular shank 29, having a suitable handle 30 at its 80 upper end, the shank being of sufficient length to pass downwardly into the casing, so that the head 27 will engage the studs. This head, as shown in Fig. 4, is provided with slots 31, the intermediate portions of which are of sufficient size to permit the heads 26 of 85 the studs to pass therethrough, said slots tapering in opposite directions, and the end portions being of less width than the diameter of the head 26, but of sufficient width to receive the stems 25 of the studs.

It is believed that the application of the valve seat 90 structure to the casing may now be readily explained. In practice, the upper ends of the threads of the valve seat sleeve 15 are preferably mutilated sufficiently to prevent the nut from completely unscrewing therefrom. This nut is raised to its highest point upon the 95 sleeve, and the studs are engaged in the slots 31 of the head 27 of the positioning tool. It will thus be clear that the valve seat member is attached to the tool and can be lowered into place. After the lugs 16 of the member have been passed through the space between 100 the lugs 13 of the casing, the tool is turned, thereby rotating the sleeve and bringing the lugs 16 beneath said lugs 13. When thus positioned, the stops 17 will prevent the further rotation of the sleeve, so that a continued revolution of the tool will cause the clamp- 105 ing nut to be screwed downwardly upon said sleeve.

As a result, the packing washer or gasket will be forced into the joint between the sleeve and casing wall 9, and consequently leakage therethrough will be prohibited. At the same time, the said nut will draw the 5 valve seat sleeve upwardly, and securely clamp the lugs 16 against the lugs 13 of the casing, thereby effectively securing the device in place. When the parts have been thus disposed, it only becomes necessary to turn the tool 30 in the reverse direction until 10 the headed studs of the nut are in the intermediate portions of the slots 31, whereupon said tool may be detached. To remove the valve seat member, the reverse of the above described operation is all that is necessary. It will thus be seen that an exceedingly simple 15 and effective valve structure is provided, which can be removed and replaced whenever found necessary or desirable.

From the foregoing, it is thought that the construction, operation, and many advantages of the herein 20 described invention will be apparent to those skilled in the art, without further description, and it will be understood that various changes in the size, shape, proportion and minor details of construction may be resorted to without departing from the spirit or sacrificing 25 any of the advantages of the invention.

Having thus fully described my invention, what I 30 claim as new, and desire to secure by Letters Patent, is:—

1. In a hydrant, the combination with a casing having 35 a valve seat receiving socket, and a portion that extends inwardly thereinto, of a valve seat member that fits in said socket, and inner and outer clamping elements carried by the valve seat member, the inner of such elements being movable past the inwardly extending portion of the casing and engaging the inner side thereof, the outer of 40 said elements being movable on the member toward and from the inner element and clamping upon the outer side of said inwardly extending portion.

2. In a hydrant, the combination with a casing having 45 a valve seat receiving socket, and a portion that extends inwardly thereinto, of a valve seat member that fits in said socket, inner and outer clamping elements carried by the valve seat member, the inner of such elements being movable past the inwardly extending portion of the casing 50 and coöperating with the inner side thereof, the outer of said elements being movable on the member toward and from the inner element and coöperating with the outer side of said inwardly extending portion, and packing interposed between one of the elements and the inwardly extending portion, said packing surrounding the member.

3. In a hydrant, the combination with a casing having 55 a valve seat receiving socket, and a plurality of spaced lugs extending inwardly thereinto, of a valve seat sleeve that fits in said socket and has a plurality of outwardly extending lugs on its lower portion that pass through the

spaces between the lugs of the casing and engage the undersides of said lugs, and a clamping nut threaded on the upper portion of the sleeve and engaging the casing to draw the member outwardly and the lugs thereof into engagement with the lugs of the casing. 60

4. In a hydrant, the combination with a casing having a valve seat receiving socket, and an inwardly extending portion, of a valve seat member that fits in said socket, clamping elements carried by the valve seat member and embracing the inwardly extending portion, said elements 65 being relatively movable on the member towards and from each other, and a packing device mounted on the member and interposed between the clamping elements, said packing device being forced by the same, upon their relative movement, into engagement with the casing to prevent 70 leakage between said casing and the member.

5. In a hydrant, the combination with a casing having a valve seat receiving socket, and an inwardly extending wall portion surrounding the same, of a valve seat sleeve that detachably engages in the socket, said sleeve having 75 a lower outwardly extending portion that engages beneath the wall portion, a clamping nut threaded on the upper portion of the sleeve, and a packing gasket located beneath the nut and forced thereby into engagement with the said wall portion of the casing. 80

6. In a hydrant, the combination with a casing having an inwardly extending wall portion provided with an opening forming a valve seat receiving socket, said wall portion having an upper beveled margin surrounding the opening and being furthermore provided with inwardly 85 extending lugs, of a valve seat sleeve that detachably engages in the opening, and is provided with lugs engaging beneath the lugs of the wall portion, said sleeve having an outer beveled portion disposed in opposition to the beveled margin of the wall and having an upper threaded 90 end, a packing gasket arranged to engage the beveled portions of the wall and sleeve, and a clamping nut threaded on the upper portions of the sleeve. 95

7. In a hydrant, the combination with a casing having a valve seat receiving socket, and an inwardly extending portion, of a valve seat member engaging in the socket, said member having an outwardly extending lug engaging the underside of the inwardly extending portion, a clamping nut threaded on the upper end of the member, and means carried by the upper side of the nut for engaging 100 the same with a positioning and locking tool.

8. In a hydrant, the combination with a casing having a valve seat receiving socket, and an inwardly extending portion, of a valve seat member engaging in the socket, said member having an outwardly extending lug engaging 105 the underside of the inwardly extending portion, a clamping nut threaded on the upper end of the member, and threaded studs projecting from the upper side of the nut and arranged to be engaged by a positioning and locking tool. 110

In testimony, that I claim the foregoing as my own, I have hereto affixed my signature in the presence of two witnesses.

JOHN PHILLIPS MERN.
